(57) **CLAIM**

The ornamental design for a lamp for photography or cinematography, as shown and described.

DESCRIPTION

The patent or application file contains at least one drawing executed in color. Copies of this patent or patent application

publication with color drawing(s) will be provided by the Office upon request and payment of the necessary fee.

1. Lamp for photography or cinematography

2. Lamp for photography or cinematography

1.1 : Front

1.2 : Back

1.3 : Left

1.4 : Right

1.5 : Top

1.6 : Bottom

1.7 : Perspective

1.8 : Perspective

1.9 : Front view of collapsed form

1.10 : Back view of collapsed form

1.11 : Left view of collapsed form

1.12 : Right view of collapsed form

1.13 : Top view of collapsed form

1.14 : Bottom view of collapsed form

1.15 : Perspective view of collapsed form

1.16 : Perspective view of collapsed form

2.1 : Front

2.2 : Back

2.3 : Left

2.4 : Right

2.5 : Top

2.6 : Bottom

2.7 : Perspective

2.8 : Perspective

2.9 : Front view of collapsed form

2.10 : Back view of collapsed form

2.11 : Left view of collapsed form

2.12 : Right view of collapsed form

2.13 : Top view of collapsed form

2.14 : Bottom view of collapsed form

2.15 : Perspective view of collapsed form

2.16 : Perspective view of collapsed form

1 Claim, 32 Drawing Sheets
